UNITED STATES PATENT OFFICE.

SOMERS VAN GILDER, OF KNOXVILLE, TENNESSEE.

HARNESS-PAD.

SPECIFICATION forming part of Letters Patent No. 376,563, dated January 17, 1888.

Application filed November 2, 1887. Serial No. 254,052. (No model.)

To all whom it may concern:

Be it known that I, SOMERS VAN GILDER, of Knoxville, in the county of Knox and State of Tennessee, have invented an Improvement 5 in Ornamenting Harness, of which the following is a full, clear, and exact description.

My invention consists of the construction, arrangement, and combination of parts, all as hereinafter described and claimed.

10 Reference is to be had to the accompanying drawings, forming a part of this specification, in which similar letters of reference indicate corresponding parts in all the figures.

Figure 1 is a perspective view of a gig-saddle having my invention applied thereto. Fig. 15 2 is a sectional view taken on the line *xx* of Fig. 1. Fig. 3 is a view of the ornament removed. Fig. 4 is a transverse sectional elevation of the same, and Fig. 5 is a sectional view of a breast-20 collar having my invention applied thereto.

A represents a strip of leather or other suitable material formed with a plain or ornamental outer edge and adapted to be stitched to one or both edges of harness-pads B, or to 25 the edge or edges of the collar C, forming a flange, which may be ornamented in any desired manner. The flanges A are each lined with a strip of fancy-colored leather or other material, *a*, stitched between the pad-leather *b*, and the skirt D, and between the said flanges 30 and the skirt D is held the leather E, which is folded at the edges to form the reed-rolls *d d*, as shown clearly in Fig. 2. Upon the outer

surface of each of the flanges A is stitched an ornamental strip, F, which is by preference 35 folded to receive the reeds *f*, which are parallel with the rolls *d*. Between the rolls or reeds *d f* is placed upon each strip F an ornamental strip or chain, G; or the outer surface of the strips F may be otherwise ornamented, as desired. By 40 this arrangement the harness may be very highly ornamented at comparatively small cost, and the strips forming the flanges may be applied to various parts of the harness.

The lining of the flanges A may, if desired, be 45 extended all the way across the bottom of the pad B, and secured to said flanges by any suitable fastening, or sewed fast to said flanges.

Having thus described my invention, what I claim as new, and desire to secure by Letters 50 Patent, is—

1. A harness - pad formed with the side flanges, A, in combination with strips F, stitched to the outer surface of the said flanges, and the ornament G, secured to the strips F between 55 their outer edges and the edges of the skirt D, substantially as shown and described.

2. The pad formed with the reed *d* at its edges, in combination with the flanges A and ornamental strip F, having the reed *f*, substantially 60 as described.

SOMERS VAN GILDER.
